Attorney

UNITED STATES PATENT OFFICE

HERBERT M. FULLER, OF BRADENTON, FLORIDA

AUTOMATIC BOOKMARK

Application filed August 2, 1930. Serial No. 472,677.

This invention relates to the automatic book mark forming the subject matter of my application filed August 13, 1929, serially numbered 385,625 and allowed June 30, 1930. 5
 5 That book mark comprises a clip adapted to be engaged with the upper edge portion of a back leaf of a book, a rigid support extending forwardly from the upper end of the clip, and an indicator carried by the support
 10 and adapted to overlie and contact with a front leaf of the book. In one form of such book mark, the indicator is slidably connected to the support and in another form thereof, the indicator is pivotally and slid-
 15 ably connected to the support, the indicator is adapted to contact with the front sides of the leaves of the book as they are successively presented thereto as the reading progresses, and the indicator is adapted to re-
 20 main in contact with the upper side of the last page presented thereto after the book has been closed.

The present invention has for one of its objects to improve and simplify the general 25 construction of the book mark, to the end that its cost of manufacture may be materially reduced, and to the end that it may be made of paper or light sheet metal or the like.

30 With the foregoing and other objects, the nature of which will appear as the description proceeds, the invention comprehends the provision of a book mark wherein the indicator shall be connected to the clip through 35 the medium of a resilient support adapted to be placed under tension during the application of the clip to a back leaf of a book and the positioning of the indicator upon a front leaf of the book, the resilient support hold-
 40 ing the indicator in flat abutting contact with the front leaf and constantly tending to move it in the direction of the clip so that it will similarly contact with the leaves as they are successively presented thereto.

45 The invention further comprehends the provision of a book mark of the character stated wherein the resilient support shall be in the form of a normally collapsed crimped strip adapted to be extended to place it un-
 50 der tension.

The invention further comprehends the provision of a book mark of the character stated which shall embody means adapted to limit the extension of the resilient support in order to prevent it from being tensioned beyond the limit of its elasticity. 55

The invention further comprehends the provision of a book mark of the character stated wherein the clip, indicator, resilient support and means for limiting the stretching of the support shall be formed from a single blank of paper or other suitable material.

The invention is hereinafter more fully described and claimed, and illustrated in the accompanying drawings, wherein:—

Figure 1 is a sectional view illustrating the application of the book mark;

Figure 2 is a plan view of the book mark;

Figure 3 is a view in end elevation of the book mark;

Figure 4 is a sectional view of a fragmentary portion of the book mark with the indicator support in extended condition;

Figure 5 is an end view of the book mark 75 equipped with a modified form of indicator support;

Figure 6 is an end view of the book mark equipped with a modified form of the means for limiting the extension of the indicator support; 80

Figure 7 is a side view of a fragmentary portion of the book mark equipped with the modified form of the means for limiting the extension of the indicator support. 85

Referring in detail to the drawings, 1 designates the clip, 2 the indicator, and 3 the resilient support. The clip comprises a base plate 4 of elongated rectangular formation in plan, and a tongue 5 struck up from the base plate near the upper end of the latter. The clip 1 is adapted to be engaged with the upper edge portion of a back leaf, such as indicated at 6, of a book 7, with its upper end portion extending beyond the upper edges of the leaves. The support 3 is in the form of a crimped strip which is attached at one end to the front side of the upper end portion of the clip plate 4, and to the front end of which the 90 95 100

indicator 2 is attached. The support 3 is in normally collapsed condition, and is adapted to be extended and flexed to develop the tension or elasticity thereof. The support 3 normally holds the indicator 2 close to the clip 1 and permits the indicator to be moved forwardly from the clip and rocked upwardly and forwardly and laterally with respect to the clip so as to permit the page 10 to be turned without drawing it downward from beneath the indicator.

The indicator 2 is of rectangular formation in plan, and extends downwardly from the front end of the support 3, and is normally maintained in parallel relation to the clip plate 4 by the support. The indicator 2 is adapted to be placed in contact with the front side of a front leaf, such as indicated at 8, of the book 7, and during the application of the indicator to this leaf it is moved forwardly with respect to the clip 1 with the result that the support 3 is tensioned and constantly tends to move the indicator in the direction of the clip 1, and in view thereof, the indicator will move into contact with the leaves between it and the clip, as they are successively presented thereto as the reading progresses. During the turning of the page with which the indicator 2 contacts, the indicator is rocked, and such movement of the indicator tensions the support 3, with the result that, after the page has been swung beyond the indicator, the support reacts and returns the indicator to 35 position for contact with the next page.

A flexible element 9 which is secured at one end to the clip 1 and at its other to the indicator 2, and which passes freely through the support 3, limits the extension of the support so as to prevent it from being tensioned beyond the limit of its elasticity.

The support 3 may consist of a single member extending transversely across the clip 1 and indicator 2, as shown in Figures 1 to 4. If desired, the support may be formed separately from the clip 1 and indicator 2 and cemented to such parts, as shown in Figures 1 to 3, or it may be formed integrally with the clip and indicator as shown in Figure 4 wherein the support is designated 3^a.

As shown in Figure 5, the support may consist of three crimped members designated 3^b, 3^c and 3^d, which may be formed separately from the clip 1 and indicator 2 and terminally secured thereto. If desired, the support member 3^c may be formed integrally with the clip 1 and indicator 2, and the support members 3^b and 3^d may be formed integrally with the indicator and attached to the clip, as indicated in this Figure. The support member 3^c is arranged with its corrugations extending transversely of the clip 1 and indicator 2, and is arranged at the center of these parts. The support mem-

bers 3^b and 3^d are arranged laterally beyond the support member 3^c and have their corrugations extending longitudinally of the clip and indicator or at right angles to the corrugations of the support member 3^c. The means for limiting the extension of the support members 3^c, 3^b and 3^d comprises a flexible element 9^a which is secured to the clip 1 and indicator 2 and passes freely through the support member 3^c.

Instead of using a flexible member for limiting the extension of the support, jointed members 10 may be employed, and when employed, they are arranged at the ends of the support 3 and terminally connected to the clip 1 and indicator 2, and these limiting members may be formed integrally with the clip and indicator or made separately and terminally cemented thereto. An elastic element 11 is terminally secured to the side edges of the clip 1 and is adapted to be engaged over the indicator 2 to hold the parts of the book mark against relative movement when it is not in use, and each form of the book mark is provided with this element. If desired, the book mark may be permanently secured to the book by cementing its part 1 to the inner side of the back cover of the book, and when this application of the book mark is resorted to, the part 1 is not made in the form of a clip but consists merely of a single strip of paper.

From the foregoing description, taken in connection with the accompanying drawings, it should be apparent that when the book mark is applied to a book in the manner illustrated in Figure 1, the indicator support is under tension and holds the indicator in full abutting contact with the front side of the leaf located forwardly of the leaf with which the clip is engaged, and that the indicator will yield readily under the pressure applied thereto by and as the result of the turning of the leaf with which it contacts, thus permitting the leaf to be turned. The indicator contacts with the next leaf, and is held in full abutting contact therewith by its support. This is continued until the leaf with which the clip is engaged is reached. When this occurs, the clip may be engaged with another back leaf, and the indicator arranged in contact with the front side of the leaf first engaged by the clip. As the indicator contacts with the leaves of the book as they are successively presented thereto, it will remain in contact with the last page presented thereto after the book has been closed. The indicator is simple and may be manufactured at a comparatively low cost. It may be manufactured from paper having the desired resilient qualities or light sheet metal or the like.

While I have described the principle of the invention, together with the structure which I now consider the preferred embodiment,

ment thereof, it is to be understood that the structure shown is merely illustrative and that such changes may be made, when desired, as fall within the scope of the invention as claimed.

I claim:

1. A book mark comprising a leaf engaging element, a page indicating element, and a crimped elastic element connecting the page indicating element to the leaf engaging element, the supporting element normally occupying a collapsed condition and adapted to be placed under tension when extended.

10 2. A book mark, comprising a leaf engaging element, a page indicating element, a crimped elastic supporting element connecting the page indicating element to the leaf engaging element, the supporting element normally occupying a collapsed condition and adapted to be placed under tension when extended, and means for limiting the extension of the supporting element.

15 3. A book mark, comprising a leaf engaging element, a page indicating element, a crimped elastic supporting element connecting the page indicating element to the leaf engaging element, the supporting element normally occupying a collapsed condition and adapted to be placed under tension when extended, and a flexible member connected to the leaf engaging element and to the page indicating element to limit the extension of the supporting element.

20 4. A book mark, comprising a leaf engaging element, a page indicating element, a crimped elastic supporting element connecting the page indicating element to the leaf engaging element, the supporting element normally occupying a collapsed condition and adapted to be placed under tension when extended, and a flexible member connected to the leaf engaging element and to the page indicating element and passing through the supporting element to limit the extension of the latter element.

25 5. A book mark, comprising a leaf engaging element, a page indicating element, an elastic element connecting the page indicating element to the leaf engaging element and constantly urging the former in the direction of the latter, and jointed members connected to the leaf engaging element and the page indicating element laterally of the elastic element and adapted to limit the movement of the page indicating element in a direction away from the leaf engaging element.

60 6. A book mark, comprising a leaf engaging element, a page indicating element, and crimped elastic members connecting the leaf indicating element to the page engaging element, one of the supporting elements being arranged with its folds extending transversely of the leaf engaging element and 65 the other of the supporting elements being

arranged with their folds extending longitudinally of the leaf engaging element.

7. A book mark, comprising a leaf engaging element, a page indicating element, and an elastic element formed integrally with 70 and connecting said first elements.

8. A book mark comprising a leaf engaging element, a page indicating element an extensible elastic supporting element formed integrally with said first elements, and 75 means for limiting the extension of the supporting element and formed integrally with one of said first elements and secured to the other of said first elements.

9. A book mark, comprising a leaf engaging element, an indicator adapted to be positioned in contact with the front side of a leaf in advance of the leaf engaged by said element, and an elastic element connecting the indicator to said first element for rocking movement upwardly and forwardly and laterally with respect thereto and adapted to normally hold the indicator in page contacting position and constantly urging the indicator in the direction of said first element.

10. A book mark, comprising a leaf engaging element, an indicator adapted to be positioned in contact with the front side of a leaf in advance of the leaf engaged by said element, and a crimped elastic element connecting the indicator to said first element for rocking movement upwardly and forwardly and laterally with respect thereto and adapted to normally hold the indicator in page contacting position and constantly urging the indicator in the direction of said first element.

In testimony whereof I hereunto affix my signature.
